UNITED STATES PATENT OFFICE

SIVERT GUNDERSEN, OF CHICAGO, ILLINOIS, ASSIGNOR TO S. KARPEN & BROS., OF CHICAGO, ILLINOIS, A CORPORATION OF WEST VIRGINIA.

SOFA-BED.

1,267,541.

Specification of Letters Patent. Patented May 28, 1918.

Application filed September 16, 1914. Serial No. 861,962.

To all whom it may concern:

Be it known that I, SIVERT GUNDERSEN, a citizen of the United States, residing at Chicago, in the county of Cook and State of Illinois, have invented a new and useful Improvement in Sofa-Beds, of which the following is a specification.

This invention relates particularly to such structures as sofa-beds, in which the back is employed as a means for locking the seat in closed position. The primary object is to provide an improved device of this character, which operates in an improved manner.

The invention is illustrated in the accompanying drawings, in which—

Figure 1 represents a view of the improved structure in open position, with one end of the frame removed; Fig. 2, a similar view showing the structure in closed position, with a portion of the frame shown brokenly; Fig. 3, a broken rear elevational view; Fig. 4, a perspective view of a latch-device employed; and Fig. 5, a perspective view of a locking-stud employed.

In the construction illustrated, A represents a frame; B, a forwardly invertible seat; C, a folding-bed normally housed in the frame below the seat; and D, a movably-mounted back for the structure.

The frame may be of any suitable construction. As shown, it comprises end-standards 1 which afford arms for the sofa; and an open-topped box 2 rigidly secured to the lower portions of the end-standards.

In the illustration given, the seat is connected, by links 3, to brackets 4 secured to the front corners of the box 2, the seat being adapted to swing forwardly from a position in which it surmounts the box 2 to an inverted position in front of the main frame.

In the form illustrated, the folding-bed C comprises a rear section 5; an intermediate or spacing-section 6, and a front section 7, the intermediate section being pivotally mounted on brackets or hangers 8 applied to the corners of the seat-frame. The sections 5 and 7 are pivotally connected with the intermediate section 6. The rear section 5 is connected by elbow levers 9 with the brackets 4; and the members 9 are joined by links 10 to the brackets 8. The section 7 is connected by links 11 to the swinging edge-portion of the seat B, and the seat B is

equipped with legs 12 operated by links 13. The rear portion of the bed-section 5 is connected, by heavy coil-springs 14, to standards 15 with which the rear corners of the box 2 are equipped. The folding-bed structure, and the manner of connecting the same and the seat to the main-frame are known in the art.

When the structure is in the folded condition shown in Fig. 2, the springs 14 tend to throw the seat open and aid in unfolding the bed-structure. The back D normally locks the seat against opening. The back D is supported on pivots 16 carried by corner standards 17 which may constitute a part of the end standards 1. These pivots are preferably located slightly below the center line of the back. Light coil-springs 18 connect the lower portion of the back to the corner standards 17 and tend to throw the lower portion of the back forward to the seat-locking position shown in Fig. 2. Clips 19 applied to the upper portions of the members 17 limit the rearward swing of the upper portion of the back. Clips 20 applied to the member 17 limit the rearward swing of the lower portion of the back. The back is equipped at its ends with downwardly-extending arms 21, upon which are pivotally mounted the latch-members 22, which have locking notches 22^a adapted to engage the studs 23 which are secured to the inner sides of the members 17. The studs 23 have attaching bases 23^a, through which screws pass to secure the studs to the members 17. The latch members 22 are provided at their front ends with extensions 22^b adapted to be engaged by arms 24 secured to the rear corners of the seat-frame, referring to the structure in the folded condition shown in Fig. 2.

When it is desired to convert the structure from sofa-form to bed-form, the upper portion of the back is drawn forward, thereby moving the latch members 22 to the latching position shown in Fig. 1, whereby the back will be restrained or held in the non-locking position. The springs 14 then operate to throw the rear edge of the seat upwardly somewhat, and assist in the operation of unfolding the structure. When the structure is closed, the seat-carried arms or cams 24 strike the forward extensions 22^b of the latching-paws and release the latch-

ing-pawls from engagement with the studs 23, whereupon the springs 18 force the lower portion of the back forward, so that the back will lock the seat in closed position, in 5 the manner shown in Fig. 2.

The latching-mechanism for holding the back in non-locking position is preferably duplicated at the two ends of the back.

From the foregoing description, it will be 10 understood that the seat may be closed without striking against or wearing the back, that the latch-members 22 are seat-released, and that the back is automatically thrown to the seat-locking position. The construction described is simple and reliable. The 15 foregoing detailed description has been given for clearness of understanding only, and no unnecessary limitation should be understood therefrom.

20 What I regard as new and desire to secure by Letters Patent is—

1. In a structure of the character set forth, the combination of a frame, a seat, means tending to turn said seat to open position, 25 a back movably mounted on said frame and adapted to lock said seat in closed position, latch mechanism acting automatically to hold the back against movement when said back is moved away from said seat, and 30 means on said seat adapted to coact with said latch mechanism to render the latch mechanism inoperative when said seat is turned to closed position.

2. A structure of the character set forth, 35 comprising the combination of the frame, a seat, means tending to turn the seat to open position, a back movably mounted on said frame and adapted to lock said seat in closed position, means acting automatically to move 40 the back to the position for locking the seat, automatic means including latch mechanism for holding the back against movement when said back is moved away from said seat, and means on said seat adapted to coact with

said latch mechanism to render the latch 45 mechanism inoperative when said seat is turned to closed position.

3. In a structure of the character set forth, the combination with a frame, of a forwardly-turning seat, means tending to 50 turn said seat to the open position, a yieldingly-held back movably connected with the frame and normally locking the seat in closed position, a latch carried by the back, latch-engaging means carried by the rear 55 portion of the frame and serving to engage the latch when the back is moved rearwardly, and latch-releasing means carried by and projecting from the rear portion of the seat.

4. In a structure of the character set forth, the combination with a frame, of a forwardly-turning seat, means tending to 60 turn said seat to the open position, a yieldingly-held back movably connected with the frame and normally locking the seat in closed position, a seat-released latch-device carried by the back and adapted to hold the lower portion of the back in retracted position while the seat is open, and means carried by the frame adapted for engagement with said latch-device.

5. In a structure of the character set forth, the combination with a frame, of a forwardly-swinging reversible seat, a folding-bed normally housed beneath and connected with the seat, a spring tending to 75 swing the seat open, a back movably mounted on the frame and normally locking the seat closed, means for moving the back to 80 the locking position, an arm depending from the back, a seat-released latch-member carried by said arm, and latch-engaging means carried by the frame.

SIVERT GUNDERSEN.
